SQUEEGEE MOP WITH WRINGER

Filed Nov. 14, 1929

Harry Hertzberg INVENTOR.

BY
Martin Joachinson
ATTORNEY.

UNITED STATES PATENT OFFICE

HARRY HERTZBERG, OF BROOKLYN, NEW YORK

SQUEEGEE MOP WITH WRINGER

Application filed November 14, 1929. Serial No. 407,108.

This invention relates to wet mops and more particularly to that type of such mops which are intended for cleaning floors and are provided with means to wring water from the mop material.

It is the object of this invention to improve the action of a mop of this kind which is provided with a squeegee plate to collect water on the floor and to absorb such water by the mop material.

The present invention carries forward the invention disclosed in my pending application for Letters Patent for "Squeegee mop" filed Sept. 5th, 1929, Serial No. 390,609.

With this and other objects in view the invention consists in certain novel features of construction, combinations of elements and arrangements of parts which will be more fully described in these specifications and finally pointed out in the appended claims.

The invention is shown in the accompanying drawings which form a material part of these specifications and in which:

Fig. 1 is a perspective elevation of my improved squeegee mop with mop cords stretched and the squeegee plate in operating position.

Fig. 2 is a plan view of Fig. 5 showing the mop in collapsed position when operating for simultaneous use of squeegee and mop.

Fig. 3 is a front elevation of my squeegee mop partly in section on line 3—3 of Fig. 4.

Fig. 4 is a sectional plan of the mop head on line 4—4 of Fig. 3.

Fig. 5 is a perspective elevation of the mop in collapsed position when squeegee and mop material are used in simultaneous operation.

Fig. 6 is a detail perspective view showing the tubular fastening means for attaching mop material to the frame.

Fig. 7 is a side elevation of Fig. 3.

Referring to the drawings, my squeegee mop consists of a mop stick 11 to the lower end of which a mop head is fastened. This head consists of two elongated metallic plates 12 and 13 adapted to lie flat upon each other. The outer side of each plate is stiffened longitudinally against bending by longitudinal ribs 12a and 13a respectively and with a central boss 12b and 13b from which the ribs

taper down towards the ends of said plates. The opposite narrow ends of plate 13 are each provided at their middle portion with an upwardly extending tooth 13c and the corresponding ends of plate 12 are each provided with cooperating notches or recesses 12c which are adapted to engage the teeth 13c when the plates are lying in juxtaposition on each other. Into the lower end of mop stick 11 a wood screw 14 is inserted in alinement with the mop stick axis. This screw has an integral cylindrical extension bolt 14a thereon which is threaded on its end portion, and thereby engages an interior thread in boss 13b, so that this boss 13b acts as a nut on bolt 14a which turns readily in a central aperture of boss 12b. Between the bolt portion 14a and the wood screw 14, a collar 14b is formed integral therewith, which is lodged in a recess of the lower end of the mop stick 11. A ferrule-cap 15, provided with a central aperture through which bolt 14a passes, is driven tightly over the lower end of mop stick 11 and against the lower annular face of collar 14b to prevent splitting of the mop stick and to form a metallic face against which boss 12b may lean.

The mop material consists preferably of two sections of rope-like strands 20, arranged sheet-like alongside of each other. One end of the so arranged mop strands 20 is interposed between the two ends of a mop fabric sheet 23 and sewed thereto by a plurality of rows of stitches 21 as shown in Fig. 6 so that the fabric sheet 23 forms a loop 24 at the end of the mop strands 20.

The free upper ends of the two mop material sections 20 are fastened to opposite sides of a sleeve 30 by means of two rings of tie wires 31 which press the cords 20 into angular grooves of said sleeve as shown in Fig. 1. In this manner the ends of each section of mop material surrounds one half of the circumference of sleeve 30 which is slidably mounted on mop stick 11 and may be held stationary thereon in raised position by means of a curved wire spring 32. In the assembled mop the two loops 24 each enclose one longitudinal half of plate 12 at opposite sides of the mop stick 11 and the mop cords extend

upwardly from plate 12 at transversely opposite sides of the mop stick 11 to sleeve 30. Below that part of the canvas 23 under plate 12 and above the top face of plate 13, a 5 squeegee plate 35 preferably made of soft rubber and of greater width and length than plates 12 and 13 is interposed. This plate has a thick portion covered by the plates 12 and 13 and tapers down towards its longitudinal edges. It is provided with three apertures, one central for bolt 14a and two near the ends for teeth 13c.

This squeegee mop is easily assembled and taken apart for cleaning or renewing the mop 15 material. By rotating the mop stick 11 plate 13 is loosened and unscrewed from bolt 14a and simultaneously teeth 13c are disengaged from notches 12c. When plate 13 is free 20 free bolt 14a the squeegee plate can be lifted off from teeth 13c. The mop material loops 25 24 can then be stripped off plate 12 in opposite directions and be removed with sleeve 30 from the upper end of the mop stick 11. It is evident that this construction permits the 30 use of the device as a simple squeegee plate with handle when the mop material and sleeve 30 are not assembled therewith, and also as a simple wringer mop when the squeegee plate is left off and the mop material with sleeve 30 are assembled with mop stick 11 and plates 12—13. For wringing, the mop cords are twisted around mop stick 11 by means of sleeve 30 in well known manner.

Fig. 1 shows the squeegee mop completely 35 arranged for squeegee operation. In this case the mop strands are stretched fan shaped along the sides of mop stick 11 and held in that position by means of the frictional engagement of spring 32 with sleeve 30.

In Figs. 2 and 5 the device is shown when 40 in operation for using squeegee and mop simultaneously, so that the action of one supplements the operation of the other. Plate 35 pushes water on a floor ahead of it and the 45 mop material absorbs it, particularly beyond the ends of plate 35 where the mop is wider than the plate as indicated by arrows in Fig. 2.

From the above description it will appear 50 clearly that this improved form of my squeegee mop has numerous advantages and novel features in addition to those recited in my afore identified copending application without any considerable addition to the number 55 of parts nor increase in its cost of manufacture.

While a preferred form of my invention 60 has been described herein, it shall be understood that modifications may be made in the design and arrangement of parts or in the construction of details which come within the scope and spirit of the invention as claimed.

Having thus described my invention what

I claim as new and desire to secure by Letters Patent is:

1. In a device of the kind described, a handle bar, a pair of parallel metallic plates of substantially equal length adapted to be held at one end of said handle bar, means to hold said plates in fixed relation to each other, a strip of mop material having one end interposed between said plates and its other end held on said handle bar, a bolt extending axially from said handle bar passing through said plates and through said mop material and mounting said plates for rotation on said handle bar, and means engaging said bolt for clamping said mop material between said plates.

2. In a device of the kind described, a handle, a pair of opposed metallic plates mounted on one end of said handle and extending perpendicularly therefrom in opposite directions, a layer of mop material having one end secured to one of said plates, a squeegee plate interposed between said plates, means to hold said plates in fixed relationship to each other, a bolt extending axially from said handle passing through apertures in said plates and means associated with the plate further from said handle and with said bolt for clamping said mop material and plates together.

3. In a device of the kind described, a handle bar, a pair of parallel metallic plates held at one end of said handle bar each of said plates having two arms extending perpendicular to the mop handle axis in opposite directions therefrom, means to hold said plates in fixed relation to each other, a bolt extending axially from said handle bar passing through apertures in said plates, mop fabric interposed between said plates forming a separate loop around each arm of one of said plates and mop cords sewed to said mop fabric.

4. In a device of the kind described, a handle bar, a sleeve slidably mounted on said bar, a pair of parallel plates at one end of said bar having arms extending from said handle in opposite directions and forming coextensive planes perpendicular to the handle axis, means to hold said plates in apposition to each other, a tubular sheath enclosing one of said plates and mop material extending from said sheath to said sleeve.

5. In a device of the kind described, a handle bar, a sleeve slidably mounted on said bar a pair of parallel plates held at one end of said bar extending perpendicularly therefrom in opposite directions, means to hold said plates in apposition to each other, mop material and a squeegee plate removably clamped between said plates, said mop material extending upwardly from said plates to said sleeve being fastened thereto, said sleeve forming means for holding said mop material in stretched

position and for dropping it over said squeegee plate.

6. In a mop, a handle, a pair of opposed metallic plates mounted on one end of said handle, mop material having one end secured to one of said plates, a squeegee plate interposed between said plates, said squeegee plate having an opening at each end thereof, an upstanding lug formed at each end of one of said metallic plates and being adapted to pass through said openings, a stem forming an extension of said handle and passing through said opposed plates and squeegee plate and means for detachably holding all of said plates in fixed relationship.

Signed at Brooklyn, in the county of Kings and State of New York, this 11th day of November, A. D. 1929.

HARRY HERTZBERG.
